UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

FEEDING MECHANISM FOR SEWING MACHINES

Application filed April 26, 1927. Serial No. 186,673.

This invention relates to new and useful improvements in feeding mechanisms for sewing machines generally, although the invention is more especially directed to a feeding mechanism for use in blind stitch sewing machines used in felling operations.

One of the principal objects of the invention is to provide upper and lower feeding mechanisms for intermittently feeding superposed layers of materials past a stitch forming mechanism, the upper layer having its marginal edge portion infolded and disposed in a substantially vertical plane for engagement by the upper feed dog whereby both the base layer and the folded upturned edge portion of the upper layer will be simultaneously fed without having a drag imparted to said folded upturned edge portion of the upper layer.

Another object of the invention is to provide upper and lower feeding mechanisms of the character described, together with means for withdrawing both the upper and lower feed dogs from operative positions whereby the material or work may be either inserted in the machine or withdrawn therefrom.

With these and other objects in view which will more fully appear, the nature of the invention will be more clearly understood by following the description, the appended claims, and the several views illustrated in the accompanying drawings.

In the accompanying drawings which illustrate one form of my invention,

Figure 1 is a front elevation of the stitching head and the work arm which form parts of a blind stitch sewing machine equipped with my invention,

Figure 2 is a left hand elevation thereof,

Figure 3 is a rear elevation of the machine.

Figure 4 is a perspective view of the upper feed mechanism and the associated parts,

Figure 5 is a plan view of the cam for operating the upper feed dog,

Figure 6 is an enlarged sectional view showing the means for permitting the lower feed dog to be depressed,

Figure 7 is an end elevation showing the normal position of the lower feed dog in full

lines and the depressed position of the dog in dotted lines,

Figure 8 is a perspective view of the operating lever for depressing the lower feed dog,

Figure 9 is an enlarged top plan view of the main presser foot showing the upper feed dog associated therewith,

Figure 10 is a bottom plan view thereof,

Figure 11 is a transverse sectional view taken on the line 11—11 of Figure 9,

Figure 12 is a perspective view of the upper feed dog and feed bar, and

Figure 13 is a side elevation of the main presser foot showing the shank of the upper feed dog supported in a guide fixed to said foot.

Like reference numerals designate corresponding parts throughout the figures of the drawings.

Referring to the accompanying drawings, I have shown in Figure 1 a base layer A which may be the body fabric of a coat and a superposed layer B which may be the lining therefor. The present invention is especially adapted for felling the lining B to the base layer or body fabric A, and to this end the superposed layer B has its marginal edge portion infolded as shown at b, and turned up into a vertical plane, as indicated at b'. By means of the sewing machine illustrated in the accompanying drawings, a line of blind stitches is formed which is disposed adjacent the meeting point between the base layer A and the upturned portion b' of the superposed layer, these stitches serving to join the two layers along a line parallel with the folded edge of the superposed layer.

After the stitching operation, the upturned folded portion of the superposed layer is returned to normal or horizontal position, thus covering the line of blind stitches formed by said stitching operation.

The blind stitch sewing machine shown in the accompanying drawings is of the Lewis type and comprises a frame which includes a base 5, a laterally extending work arm 6, a standard 7, an overhanging arm 8, and a stitching head 9 which is secured to the free end of the overhanging arm 8 and is dis-

posed above the outer end of the work arm 6.

The machine includes a stitch forming mechanism which I have indicated as a whole by the reference numeral 10, and a work presenting mechanism which I have indicated as a whole by the reference numeral 11. Both the stitch forming mechanism 10 and the work presenting mechanism 11 are operated from a rotary shaft 12 which extends longitudinally of the overhanging arm 8 and across the standard 7. A grooved pulley 13 is fixed to the shaft 12 opposite the stitching head 9 and is adapted to be driven by any suitable power.

The work presenting mechanism is shown and claimed in my co-pending application Serial No. 186,674, filed April 26, 1927. This work presenting mechanism includes a main presser foot 14 which is fixed to the stitching head 9, a work clamp 15 which cooperates with the work below the main presser foot, a lower feeding mechanism 16, an upper feeding mechanism 17, a lower plunger mechanism 18, an upper plunger mechanism 25 and a movable presser foot 20.

The stitch forming mechanism 10 includes a reciprocating needle 21 having its path of movement in or parallel with the line of feed. The needle 21 is secured to the arm 22 of a needle lever 23 which is journaled on a fixed shaft 24 secured to the stitching head 9. The needle lever 23 is mounted on the stub shaft 24, not only for oscillatory movements about said shaft, but also for lateral movements longitudinally of said shaft. The other arm of the needle lever 23 is pivotally connected with the lower end of a link 27, the upper end of said link being pivotally connected as at 28 to one arm of a bell crank lever 30 which is journaled on the stitching head 9, the other arm 31 of the bell crank lever being pivotally connected as at 32 with the lower end of a link 33. The upper end of the link 33 is connected to an eccentric pin 34 formed on a jack shaft 35 which is journaled in the stitching head 9 below the main shaft 12 and extends in parallelism therewith. A "1 to 1" gear coupling 35^a connects the main shaft 12 and the jack shaft 35 and consequently during each complete rotation of the main shaft 12 the needle 21 is thereby given a complete reciprocation in the line of feed.

It is desirable to impart a shogging motion to the needle 21 whereby the needle during one reciprocation will enter the base layer and emerge therefrom and whereby during the following reciprocation the needle will enter the folded upturned portion of the lining. To this end, I have provided the following mechanism which will impart a positive lateral shifting movement to the needle lever 23:

The needle lever 23 is formed with a hub extension 36 journaled on the stub shaft 24 and this hub extension is formed with a pe-

ripheral groove 37 which receives a slide block 38 secured to the lower end of an arm 39 of a bell crank lever 40, said lever 40 being fulcrumed as at 41 to the stitching head 9. The other arm 42 of the bell crank lever is provided at its outer end with a fork 43 for engagement with an actuating cam 44. The cam 44 is fixed to a shaft 45 which is journaled in the stitching head 9 and has its longitudinal axis disposed in parallelism with the line of feed. The cam shaft 45 is rotated once to every two revolutions of the main shaft 12. In order to thus rotate the cam shaft 45, I have journaled a substantially vertical shaft 46 on the stitching head 9, and this shaft 46 is driven from the gear coupling 35^a through the medium of a gear 47 fixed to said shaft 46. Fixed to the shaft 46 is a worm 48 which drives a pinion 49 fixed to the cam shaft 45. The cam 44 is of the peripheral type and includes two separated concentric portions. These concentric portions are oppositely disposed and are of different radii. As the result of the positive driving connection between the cam 44, the bell crank lever 40 and the needle lever 23, the latter will be oscillated along the stub shaft 24 while the needle is in its forward position. The cam shaft 45 rotates in an anti-clockwise direction as viewed from the front of the machine and consequently when one concentric portion is disposed above the axis of the cam shaft, the bell crank lever 40 is in a position whereby the needle will reciprocate in its lefthand position, whereas when the other concentric portion of the cam is above the axis thereof, the bell crank 40 will be shifted so that the needle will reciprocate in its righthand position.

Cooperating with the needle 21 to form a line of straight-away stitches is a rotary hook 52, and this hook is given two complete rotations to each reciprocation of the needle. The hook is fixed to a shaft 53 (see Figure 3), and fixed to this shaft is a bevel gear 54 which is driven from a corresponding bevel gear 55 fixed on the vertical shaft 46. Inasmuch as the gear coupling 54-55 is a "1 to 1" coupling, the hook 52 will be rotated once during each rotation of the vertical shaft 46.

The presser foot 14 is fixedly secured to the lower portion of the stitching head 9, and cooperating with the under face of the presser foot is the work clamp 15, the lower feed mechanism 16, and the lower plunger mechanism 18.

The lower feeding mechanism 16 includes a feed dog 56 which is of the 4-motion type, and the mechanism for operating this feed dog is substantially identical with that shown in my former Patent 1,588,132, issued June 8, 1926. The backward and forward movement of the feed dog is obtained through the medium of a rock shaft 57, which I term the

"feed travel" shaft, and the up and down movement of the feed dog is obtained from a rock shaft 58, which I term the "feed lift" shaft. These rock shafts 57—58 extend longitudinally within the work arm 6 and have their righthand ends journaled in a bearing lug 59 and their lefthand ends journaled in bearings formed in a block 60 which is detachably secured to the lefthand end of the work arm by screws 61. Fixed to the outer end of the "feed travel" shaft 57 is a rock arm 62, and pivotally connecting the outer ends of the rock arm and the forward extremity of the feed dog 56 is a link 63. The rock arm 62 extends in a general vertical direction and the link 63 extends in a general horizontal direction. Thus upon movement of the rock arm 62, the link 63 will impart backward and forward movements to the feed dog 56. The feed dog is pivotally connected, as at 64, to the upper end of a substantially vertically disposed link 65, the lower end of the link being pivotally connected, as at 66, to the horizontal arm 67 of a bell crank lever 68, the vertical arm 69 of the bell crank lever being pivotally connected as at 70 to one end of a link 71, the other end of said link 71 being pivotally connected as at 72 to the outer end of a vertically disposed rock arm 73 fixed to the "feed lift" shaft 58. In order to maintain the feed surface of the feed dog in a substantially horizontal plane during the feed movements thereof, I have provided a spring 74 which is connected by a pin 75 fixed to the link 65 and a pendent tail 76 fixed to the feed dog. It will, therefore, be observed that upon rocking movement of the "feed lift" shaft 58, the vertical link 65 will be bodily raised and lowered, and consequently the feed dog will be given its up and down movements. By proper timing of the shafts 57 and 58, a 4-way feed motion will be imparted to said dog.

The bell crank lever 68 is pivotally connected, as at 77 to a head 78 secured to the lower end of a guide post 79, said head and post forming a vertically movable carrier. The post 79 is mounted for vertical sliding movements in a bore formed in the end block 60, and this block is formed with a seat 80 for engagement by the head 78 to limit the upward movement of the carrier. The carrier is normally held in its highest position, that is, with the head 78 bearing against the seat 80, by means of a flat spring 81, the inner end of which is rigidly secured to the work arm 6 and the outer end thereof is disposed under the head 78 so as to yieldably retain the carrier in its highest position. The upper end of the post 79 projects above the block 60 and carries a pair of rearwardly projecting arms 82—82 between which is pivoted, as at 83, the work clamp 15.

From the foregoing, it will be observed that when the feed dog 56 is elevated to its high-

est position, the fulcrum of the bell crank lever 68 is then shifted to the pivot 66, and consequently the last part of the rocking movement of the crank arm 73 will cause the bell crank lever 68 to be moved downwardly about its fulcrum 66, thus lowering the work clamp 15. The parts are so timed that the work clamp is lowered prior to the feeding movement of the feed dog. The reverse order of movement will take place at substantially the time the feed dog reaches the end of its feeding stroke, thus causing the clamp to engage the fabric and clamp the latter against the bottom of the main presser foot 14 so as to retain the fabric against movement while the needle is penetrating the material and emerging therefrom.

In order to rock the "feed travel" shaft 57 and the "feed lift" shaft 58, I provide the main shaft 12 with two eccentrics. A connection rod 84 has its upper end engageable with one of said eccentrics and has its lower end pivotally connected to a rock arm fixed to the "feed travel" shaft 57. A connection rod 87 has its upper end engageable with the other eccentric mounted on the main shaft and has its lower end pivotally connected to a rock arm fixed to the "feed lift" shaft 58. The connection rods 84 and 87 are disposed within the standard 7 of the machine frame, and the eccentrics which are mounted on the main shaft for actuating these rods are timed so as to bring about a 4-motion movement to the feed dog.

In order to position the base layer A whereby the needle 21 will penetrate and emerge therefrom, I have provided the lower plunger mechanism 18 which includes a vertically reciprocating plunger 91 which is disposed directly below an opening 90 formed in the presser foot 14 and directly below the stub shaft 24 which supports the needle lever 23. The plunger 91 is reciprocated vertically through the medium of a plunger shaft 92 which is journaled in and extends longitudinally of the work arm 6, said plunger shaft 92 being oscillated by the main shaft 12 through the medium of a connection which I have indicated as a whole by the reference numeral 93. This particular plunger operating mechanism forms the subject matter of my co-pending application, Serial No. 186,672, filed April 26, 1927, and it is therefore believed that further description will be unnecessary.

The main presser foot 14 includes a heel 94 and a toe 95, the opening 90 being located therebetween. The foot 14 includes at its front end an offset portion 96 which is spaced from the toe 95 to form a longitudinally extending and vertically disposed guideway 97 for the upturned folded portion B' of the lining B. This guideway extends in the line of feed and includes a vertical wall 98 which is carried by the toe 95, the wall being disposed

on the lefthand side of the path of needle oscillation. The wall 98 extends rearwardly past the opening 90 and terminates in the heel 94, as indicated at 99 in Fig. 10. Co-operating with the guide wall 98 is the horizontally movable presser foot 20 and horizontally movable upper plunger 100, the foot 20 extending substantially across an opening 101 formed in the wall 98 and the plunger 100 being mounted for reciprocatory movements through said opening 101 to project the node of the upturned folded portion b' into the path of needle oscillation. Inasmuch as the specific construction of the movable presser foot 20, the upper plunger 100, the means for withdrawing said movable presser foot 20 from operative position, and the means for actuating the upper plunger is shown, described and claimed in my co-pending application above mentioned, Serial No. 186,672, it is thought that further description of these parts will be unnecessary.

The upper feed mechanism 17 includes a feed dog 102 which is connected to the feed bar 103 having an upwardly extending and longitudinally disposed guide plate 104. The feed dog 102 is disposed in rear of the offset portion 96 of the presser foot 14, and means are provided for imparting four motions to said dog. The feed dog 102 is provided with a series of teeth 105, and this feed dog is positioned directly above the bottom of the presser foot 14 whereby the said teeth will cooperate with the guiding wall 98 and clamp the upturned folded edge portion b' therebetween. The feed dog is supported for its horizontal movements by means of a guide 106 which is attached to the lefthand side of the presser foot 14, said guide including upper and lower horizontal arms 107 and 108 respectively for receiving the shank of the feed dog 102. For imparting backward and forward movements to the feed dog 102, that is, movements in the line of feed, I have provided an actuating lever 109 which is fulcrumed on a horizontal pivot 110 fixed to the stitching head 9. The lower arm 111 of said lever is connected to the rear end of the feed bar 103 through the medium of a horizontal pivotal connection 112, and a vertical pivotal connection 113. The upper arm 114 of said lever is provided with a segmental slot 115 to which is adjustably connected as at 116 the rear end of a link 117 which has its forward end pivoted to an eccentric pin 119 fixed to the shaft 35. Consequently, during each complete rotation of the main shaft 12, the lever 109 will be given a complete reciprocation, and as a result the feed dog 102 will be given its backward and forward movements. In order to reciprocate the feed dog 102 laterally, that is, toward and away from the upturned edge portion b' of the lining B, I have provided an actuating lever 120 which is vertically disposed and is mounted to oscillate

in a plane at right angles to the lever 109. The lever 120 is provided at its lower end with a groove 121 for continuous although sliding contact with the guide plate 104 carried by the feed bar 103 so as to permit said feed bar to move longitudinally in the line of feed. The lever 120 is fulcrumed intermediate its ends on a crank pin 122 fixed to a crank shaft 123 journaled in the stitching head 9. The crank shaft has its longitudinal axis in the line of feed, and secured to the rear end of this crank shaft is a rock arm 124. A spring 125 has one end fixed to the rock arm 124 and the other end fixed to the stitching head 9. The upper end of the actuating lever 120 carries a roller 126 for engagement with a peripheral cam 127 fixed on the shaft 45. The cam 127 is provided with oppositely disposed high points or concentric portions 128—128 and opposed intermediate eccentric portions 129—129, the former having a common radius. A spring 130 has one end connected to the upper arm of the lever 120 and the other end connected to the stitching head 9. The spring 130 functions to yieldably retain the cam roller 126 in constant engagement with the actuating cam 127. The spring 125 serves to yieldably retain the cam shaft 123 against movement, and consequently yieldably retain the fulcrum of the lever 120 against movement.

Thus when a seam or other abnormally thick portion in the upturned folded portion b' of the lining is being fed through the machine, the fulcrum 122 of the lever 120 will yield and thereby avoid any choking action to the feed of the material which would otherwise occur by reason of the guiding wall 98 being immovable.

In order to depress the lower feed dog 56 from working position relative to the presser foot 14, and to simultaneously withdraw the upper feed dog 102 laterally away from working position, I have provided the following manually controlled mechanism:

In order to permit the work to be inserted in the machine or to be withdrawn therefrom, it is desirable to provide means for depressing the lower feed dog 56 from co-operative relation with the main presser foot 14 and to move the upper feed dog 102 laterally away from the fixed guiding wall 98. I have, therefore, provided a manually operable means for this purpose. This manually operable means includes a lever 131 which is journaled on the plunger operating shaft 92 through the medium of two bearing arms 132—132. The lever 131 extends longitudinally of the work arm 6 and has its outer end provided with an offset projection 133 which engages directly above the head 78 of the post 79 to which the bell crank lever 68 of the lower feed mechanism is pivoted. The inner end of the lever 131 is provided with an operating extension 134 which is normally disposed

in a substantially horizontal plane and is located within the base 5. A spring 135 connects one of the bearing arms 132 with the base 5 for the purpose of yieldably retaining the lever 131 against undesirable vibrations. A foot treddle, knee press, or any other manual means, is adapted to be connected with the operating extension 134 so as to oscillate the lever 131 and depress the post 79 against the tension of the spring 81. When the post 79 is thereby lowered, the fulcrum 77 of the bell crank lever 68 will be bodily moved downwardly therewith and as a result the link 65 together with the feed dog 56 will be lowered simultaneously, thereby permitting work to be inserted under the main presser foot 14 or to be withdrawn therefrom. In order to withdraw the top feed dog 102 from cooperative engagement with either the fabric B or the guiding wall 98 so as to easily insert the folded marginal portion b' in the guideway 97 or withdraw the fabric therefrom, I have provided a vertically disposed push rod 136 having its lower end pivotally connected to the rock arm 124 of the crank shaft 123. The push rod 136 is mounted in bearings formed in the stitching head 9. Mounted upon the stitching head 9 is a horizontally disposed operating lever 137 which is fulcrumed at 138. One end of the lever 137 is normally disposed above and in contact with the upper end of the push rod 136, and pivotally connected to the other end of the lever 137 is a push rod 139 which is guided intermediate its ends in a bearing 140 formed in the standard 7 of the machine frame. The lower end of the push rod 139 rests upon the operating arm 134 of the lever 131 which is fulcrumed on the plunger operating shaft 92. As a result, when the arm 134 is elevated through the medium of a knee press, treddle, or the like, the lever 131 will be oscillated and the lower feed dog 56 will be lowered from cooperative engagement with the presser foot 14, as previously described. Simultaneously with this movement, the push rod 139 will be moved upwardly, the lever 137 will be oscillated, the push rod 136 will be moved downwardly, the crank shaft 123 will be oscillated against the tension of the spring 130, and consequently the fulcrum 122 of the upper feed dog actuated lever 120 will be shifted outwardly thereby moving the upper feed dog 102 outwardly from cooperative relation relative to the marginal folded portion b' or the fixed guiding wall 98. After the removal or insertion of the material, the manually controlled means is released and the spring 81 will return the lower feed dog 56 to its initial position. The spring 135 will return the lever 131 to its initial position and the spring 130 will return the lever 120, the crank shaft 123 and the operating lever 137 to their initial positions.

65 It is of course to be understood that the

details of structure and arrangements of parts may be variously changed and modified without departing from the spirit and scope of my invention.

I claim:

1. In a feeding mechanism for sewing machines, the combination with two work feeding devices operating in planes at right angles to each other to feed the work in the same direction, yieldable means for normally holding said feeding devices in operative engagement with the work, and manually controlled means for moving said feeding devices out of operative working positions. 70
2. In a feeding mechanism for sewing machines, the combination with a work support, a lower four-motion feed cooperating therewith to feed the work, an intermittent feed above the work support operating in a plane at right angles to the lower feed and cooperating therewith to feed the work in the same direction, and manually controlled means for moving the lower feed downwardly and the upper feed laterally out of operative working positions. 80
3. In a feeding mechanism for sewing machines, the combination with a work support, a lower four-motion feed cooperating therewith to feed the work, a four-motion feed above the work support operating in a plane at right angles to the lower feed and cooperating therewith to feed the work in the same direction, manually controlled means for moving the lower feed downwardly and the upper feed laterally out of operative working positions, and means for operating said feeds in unison. 90
4. In a feeding mechanism for sewing machines, the combination with a feed bar having a feed dog, a lever fulcrumed on an axis transverse to the line of feed for reciprocating said bar longitudinally in the line of feed, and a lever having a sliding connection with said bar for reciprocating the latter in a plane at substantially right angles to the longitudinal axis of the bar, said levers being located on the same side of the feed bar and being fulcrumed on pivots whose axes are in planes at right angles to each other. 105
5. In a feeding mechanism for sewing machines, the combination with a feed bar having a feed dog, means for reciprocating said bar longitudinally in the line of feed, a lever mounted on a shiftable fulcrum and having a sliding connection with said bar for reciprocating the latter in a plane at substantially right angles to the longitudinal axis of the bar, means for yieldably retaining said fulcrum in operative position, and manually controlled means for shifting said fulcrum against the tension of said yieldable means for moving said feed dog out of operative working position. 115
6. In a feeding mechanism for sewing machines, the combination with a feed bar having a feed dog, means for reciprocating said bar longitudinally in the line of feed, a lever mounted on a shiftable fulcrum and having a sliding connection with said bar for reciprocating the latter in a plane at substantially right angles to the longitudinal axis of the bar, means for yieldably retaining said fulcrum in operative position, and manually controlled means for shifting said fulcrum against the tension of said yieldable means for moving said feed dog out of operative working position. 125

ing a feed dog, means for reciprocating said bar longitudinally in the line of feed, an oscillatory shaft extending parallel to the line of feed and having a crank pin, a lever fulcrumed on said crank pin and having one end operatively connected to said feed bar for reciprocating the latter in a plane at substantially right angles to the longitudinal axis of the feed bar, and means for oscillating said shaft to shift the fulcrum of the lever for moving the feed dog out of operative working position.

7. In a feeding mechanism for sewing machines, the combination with a feed bar having a feed dog, means for reciprocating said bar longitudinally in the line of feed, an oscillatory shaft extending parallel to the line of feed and having a crank pin, a lever fulcrumed on said crank pin and having one end operatively connected to said feed bar for reciprocating the latter in a plane at substantially right angles to the longitudinal axis of the feed bar, means for yieldably retaining said shaft against oscillatory movements, and means for oscillating said shaft against the tension of said yieldable means to shift the fulcrum of the lever for moving the feed dog out of operative working position.

8. In a feeding mechanism for sewing machines, the combination with a feed bar having a feed dog, means for reciprocating said bar longitudinally in the line of feed, an oscillatory shaft extending parallel to the line of feed and having a crank pin, a lever fulcrumed on said crank pin and having one end operatively connected to said feed bar for reciprocating the latter in a plane at substantially right angles to the longitudinal axis of the feed bar, means for yieldably retaining said shaft against oscillatory movements, means for oscillating said lever including a peripheral cam having direct contact with the other end of the lever, a spring for maintaining said lever in contact with said cam, and means for oscillating said shaft against the tension of said yieldable means to shift the fulcrum of the lever for moving the feed dog out of operative working position.

9. In a top feed mechanism for sewing machines, the combination with a frame including a horizontal work support and a head disposed above the same, of a feed bar including a feed dog carried by the head for feeding the work rearwardly between the work support and the head, said feed dog having its work engaging surface disposed in a vertical plane, a lever fulcrumed on the head and having pivotal connection with the rear end of the feed bar for reciprocating said bar longitudinally in the line of feed, and a lever fulcrumed on the head and having a sliding connection with the front end of the feed bar for reciprocating said bar in a plane

at substantially right angles to its longitudinal axis.

10. In a top feed mechanism for sewing machines, the combination with a frame including a horizontal work support and a head disposed above the same, of a feed bar including a feed dog carried by the head for feeding the work rearwardly between the work support and the head, said feed dog having its work engaging surface disposed in a vertical plane, a rotary shaft journaled in said head, an eccentric on said shaft, a vertically disposed lever fulcrumed on the head and having its lower end pivotally connected to the rear end of the feed bar for reciprocating said bar longitudinally in the line of feed, a link connecting the eccentric and the upper end of the lever, a lever fulcrumed on the head and having a sliding connection with the front end of the feed bar for reciprocating said bar in a plane at substantially right angles to its longitudinal axis, and operating connections between said shaft and said second lever.

11. In a top feed mechanism for sewing machines, the combination with a frame including a horizontal work support and a head disposed above the same, of a feed bar including a feed dog carried by the head for feeding the work rearwardly between the work support and the head, said feed dog having its work engaging surface disposed in a vertical plane, a rotary shaft journaled in said head, an eccentric on said shaft, a vertically disposed lever fulcrumed on the head and having its lower end pivotally connected to the rear end of the feed bar for reciprocating said bar longitudinally in the line of feed, a link connecting the eccentric and the upper end of the lever, a lever fulcrumed on the head and having a sliding connection with the front end of the feed bar for reciprocating said bar in a plane at substantially right angles to its longitudinal axis, and operating connections between said shaft and said second lever including a counter shaft, a peripheral cam fixed on said counter shaft and having direct contact with said second lever, and a spring connecting the second lever and head for maintaining said contact between the lever and cam.

12. In a top feed mechanism for sewing machines, the combination with a frame including a horizontal work support and head disposed above the same, of a feed bar including a feed dog carried by the head for feeding the work rearwardly between the work support and the head, said feed dog having its work engaging surface disposed in a vertical plane, a lever fulcrumed on the head and having pivotal connection with the feed bar for reciprocating said bar longitudinally in the line of feed, a rock shaft journaled in the head and extending parallel to the line of feed, a crank pin mounted on the

rock shaft, a spring connection between the head and the rock shaft for yieldably retaining the shaft against rocking movement, a lever fulcrumed on said crank pin and having connection with the feed bar for reciprocating the bar in a plane at substantially right angles to its longitudinal axis, means for oscillating said lever, and means for oscillating said rock shaft against the tension of said yieldable means to shift the fulcrum of the lever for moving the feed dog out of operative working position.

13. In a feed mechanism for sewing machines, the combination with a work support, of a presser foot having a vertical guideway extending rearwardly from its front end, an oscillatory needle movable across the guideway, one wall of the guideway extending in rear of the path of needle oscillation, a four motion bottom feed cooperating with the presser foot to feed the material along the guideway past the path of needle oscillation and including a feed dog having its teeth in a horizontal plane, and a four motion top feed cooperating with the rear wall of the guideway to feed the seamed material rearwardly away from the path of needle oscillation, and including a feed dog having its teeth in a vertical plane.

30 In testimony whereof I hereunto affix my signature.

CHARLES W. MUELLER.
